ROOF AND ROOFING MATERIAL

David E. Gray, Corning, N. Y., assignor to Corning
Glass Works, Corning, N. Y., a corporation of
New York

Application August 23, 1940, Serial No. 353,937

2 Claims. (Cl. 108—10)

This invention relates to roofs and roofing materials, and more particularly to a novel form of tile or fabricated shingle and the roof covering built up therewith.

The primary object of the invention is a strong durable roof which is weather tight, economical both of material and labor of installation, and attractive in appearance.

A further object of the invention is a tile, shingle or roofing unit which is adapted to cooperate with similar units to form a tight roof in which a large portion of the unit is exposed to the weather.

A still further object of the invention is a novel means of fastening the individual units to the supporting structure and of locking the units together to prevent their displacement from their installed position.

This invention includes among its features a roofing unit comprising a section adapted to be exposed to the weather and including in its upper surface raised or embossed portions for deflecting the flow of water from different points thereon, a body portion directed at a slight angle to the exposed section and adapted to underlie the succeeding course of roofing units, and a transverse flange along the end of said body portion adapted to cooperate with fastening means attached to the supporting structure.

Further features of the invention include an assembled roof structure formed of the novel roofing units in which one course of units tends to divert surface flow thereon away from the joints of such course as well as from the joints in the next lower course and in which each course is locked against lifting by the cooperation of surface contacting portions of one course with the otherwise free edge of an adjacent course.

Further features of the invention will be readily apparent from an understanding of the preferred form of the invention hereinafter more fully described and illustrated in the accompanying drawing in which

Fig. 1 is an end view of a roof formed of the roofing units of the present invention;

Fig. 2 is a perspective view of a number of units assembled as in a roof; and

Fig. 3 is a perspective view of a single full roofing unit incorporating the features of the present invention.

As will readily be seen, the majority of the tile or shingle units are composed of two integrally formed flat, rectangular sections 10 and 12 arranged at a slight angle to one another.

Section 10 is for convenience termed a body section and section 12 an exposed section. The end of the body section remote from the exposed section has an upstanding flange 14 for mounting of the tile on the roof boards or the like, but in other respects has a plain flat upper surface, whereas the exposed section 12 has triangular wedge shaped raised or embossed pyramidal portions 16, 18 and 20 for diverting water away from the lines of juncture of the respective units when assembled in a roof structure. As above stated, the majority of the units are shaped as above described. However, other tiles 22 comprising body sections only are employed in the first or lowermost course of a roof assembly. Also left hand units, such as 24 and similar right hand half units (not shown), are employed in each alternate course laid in order to stagger the lines of juncture of the tiles of one course with respect to another. For the same reason half width body tile units 26 are also employed.

As illustrated, all tile units are attached to the roof boards by means of clamping strips 30. In a typical roof structure the first horizontal row or course of units laid is composed of a unit 26 at at least one end of the row, with the necessary number of units 22 to cover the roof breadth. The second course is composed of units 6 which are so laid as to entirely cover the units 22 and 26 and to have their lines of juncture staggered with respect to those of the latter units. The subsequent course is composed of units 24 and 6 arranged with their lines of juncture staggered with respect to the units of the preceding course and with their exposed sections butting against the upper ends of portions 16 and 18 of the previously laid row of units. The subsequent rows of units are laid in a similarly obvious fashion until the ridge of the roof structure is approached. A suitable capping member 28 spans opposite sides of the roof edge and projects down either side thereof into abutting relation with the upper edges of the raised portions 16 and 18 of the last laid course of units.

As will be evident, adjoining raised or embossed portions 16 and 18 divert water away from the juncture of the adjoining units of the course in which they form a part, whereas the raised portions 20 divert the water from the line of juncture of the units in the course below them. Any small amount of water which does pass between units will have its line of flow directly toward the apex of a raised portion 20 which, as already stated, simply diverts the flow of such

water away from the line of juncture of the two units meeting below portion 28.

The portions 16 and 18 by butting against the lower ends of the exposed sections 12 tend to divert up-moving wind currents over such sections thereby materially reducing the danger of the tiles being lifted by the wind. Also, as will be evident from a consideration of Fig. 1, the presence of raised portions 16 and 18 on the surface of a section 12 results in a positive locking of the units in the position in which they are originally laid so long as the uppermost course of units is held in position by cap 28. Any attempt to lift an intermediate or lower course of units tends to cause the next higher course to rotate about its fastening 38 as a center and, since the points of rotation of adjacent courses are separated by a distance equal to less than half the length of each unit, the lower edge of the upper unit tends to slide toward the lower end of the unit being raised, i. e., the radii drawn from the centers of rotation to the point of intersection tend to equalize. Such sliding movement is positively opposed by abutment of the free ends of each course against the raised portions 16 and 18 of the next lower course and accordingly all lifting of units throughout the entire roof is prevented.

Although in the foregoing there has been shown and described the preferred embodiment of the invention, it is to be understood that minor changes in the details of construction and combination of units may be resorted to without departing from the spirit and scope of the invention as claimed.

I claim:

1. In a roof structure successive courses of roofing tile with the line of juncture of the respective tiles of one course staggered with respect to those of the succeeding course and the respective tiles of each course having embossed inverted right angled triangular surface portions with their altitudes located along the lateral edges of the tiles in registry with one another, and at least 5 certain of the tiles of certain courses also each having an embossed triangular surface portion having its base arranged in register with the bases of adjoining embossed portions of tiles in a course immediately below it.
- 15 2. In an assembly, for covering a roof structure, a course of tile or shingle units each having a flat top surface with the upper end turned up, clamping means cooperative with the up-turned ends of said units to hold them on the roof structure, a second course of units overlapping those of the first course and in staggered relation thereto, the units of said second course having embossed areas with surfaces for diverting water flowing thereover in directions away from their 20 lateral edges, a third course of units overlapping those of the second course and in staggered relation thereto, the lower ends of the units of the third course abutting the embossed areas of the second course of units and themselves having embossed areas with surfaces for diverting water 25 flowing thereover in directions away from the lines of juncture of the respective units of the tiles of the second course.
- 30

DAVID E. GRAY.
